John A. Straight

United States Patent Office.

JOHN A. STRAIGHT, OF ALBION, NEW YORK.

Letters Patent No. 93,922, dated August 17, 1869.

IMPROVEMENT IN BOILER-FURNACES.

The Schedule referred to in these Letters Patent and making part of the same.

To all whom it may concern:

Be it known that I, JOHN A. STRAIGHT, of Albion, in the county of Orleans, and State of New York, have invented a new and improved Boiler-Furnace; and I do hereby declare the following to be a full, clear, and exact description thereof, sufficient to enable others skilled in the art to which my invention appertains, to make and use the same, reference being had to the accompanying drawing, forming part of this specification, in which—

Figure 1 is a central vertical longitudinal section.

Figure 2 is a transverse vertical section in line *o o*, fig. 1.

Similar letters of reference indicate corresponding parts in the two figures.

My invention relates to a furnace for boilers, in which the gaseous products evolved from the burning fuel are thoroughly intermixed with atmospheric air, at a point where the intensity of the heat in the furnace shall insure a perfect combustion of the gaseous products of the fuel.

It consists in providing an opening or openings in the bridge-wall, at or about the rear of the furnace and the chamber behind the bridge-wall, which opening shall convey the products of combustion in the furnace to the chamber leading to the smoke-stack.

I surround this opening (partially or wholly) by another opening or openings, which shall communicate with the atmospheric air outside of the furnace.

By these means is caused a thorough concentration of the products of combustion at the opening or openings through the bridge-wall, and an intermixture therewith of a suitable proportion of atmospheric air, through the opening or openings which surround it, to perfect combustion.

In the drawings—

A represents a boiler, *B*, the furnace, and *C*, the grate thereof, all of which may be of the ordinary form and construction.

D is the bridge-wall at the back part of the furnace, and in which is formed an opening or openings, *E*, for the passage of the products of combustion from the furnace to the passage-way to the smoke-stack.

In the present case this opening or openings commence at a point below the top of the bridge-wall *D*, and gradually incline upward to its termination, so as to form an oblique passage.

This opening may also extend horizontally through the bridge-wall *D*.

G represents an air-passage in the bridge-wall *D*, partially or wholly surrounding the opening or openings *E*, and connecting, by a passage, *F*, with the atmosphere outside the furnace, said passage being provided with the damper *H*, to control the admission of the air.

The operation is as follows:

A fire being kindled, and a sufficient degree of heat being obtained, the products of combustion are carried toward the wall *D*, and, intermingling with the air from the passages *G* and *F*, are concentrated at the opening *E*, thus causing a thorough intermixture of the products of combustion and the air, under an intense degree of heat, they being carried through the opening *E*, and directed against the bottom of the boiler, and again deflected into the chamber behind the bridge-wall *D*, thus increasing the intermixture of the particles, and perfecting combustion.

The high degree of heat that is maintained at the point where the air is admitted, insures thorough combustion, thereby creating an intense flame, and causing a saving in the consumption of the fuel, and preventing the formation of smoke, as it is a well-known principle in chemistry that the hotter the products of combustion are, the greater will be their affinity for the oxygen of the air.

What I claim as new, and desire to secure by Letters Patent, is—

The opening *E* in the bridge-wall *D*, in connection with the passage *G F*, constructed and arranged, in relation to the furnace *B*, substantially as set forth.

JOHN A. STRAIGHT.
